(57) CLAIM

The ornamental design for a planter, as shown and described.

DESCRIPTION

FIG. 1 is a perspective view illustrating my ornamental design for a planter;

FIG. 2 is a top view of the planter shown in FIG. 1;

FIG. 3 is a bottom view of the planter shown in FIG. 1;

FIG. 4 is a side view of a representative side of the planter shown in FIG. 1;

FIG. 5 is a perspective view illustrating a second embodiment of my ornamental design for a planter;

FIG. 6 is a top view of the planter shown in FIG. 5;

FIG. 7 is a bottom view of the planter shown in FIG. 5; and, FIG. 8 is a side view of a representative side of the planter shown in FIG. 5.

The broken lines in the drawings represent unclaimed environmental subject matter and form no part of the claim.
